UNITED STATES PATENT OFFICE.

HENRY C. SPALDING, OF BROOKLYN, NEW YORK.

IMPROVED TREADLE-STAND.

Specification forming part of Letters Patent No. 23,048, dated February 22, 1859.

To all whom it may concern:

Be it known that I, HENRY C. SPALDING, of Brooklyn, in the county of Kings and State of New York, have invented a new and Improved Treadle-Stand for Sewing-Machines; and I do hereby declare that the following is a full and exact description thereof, reference being had to the accompanying drawings, and to the letters of reference marked thereon.

Figure 1 is a back view of my improvement. Fig. 2 is a side view. Fig. 3 is a top or plan view with the table removed.

Similar letters of reference indicate corresponding parts in the several figures.

This invention relates to a new and improved self-sustaining treadle frame or stand for sewing-machines.

To enable others skilled in the art to make and use my invention, I will proceed to describe its construction and operation.

A represents a table on which the sewing-machine is to be placed; B, the treadle; C, the treadle-shaft; D, the crank and crank-shaft; E, the connecting rod or pitman. All of these may be made in the ordinary manner and similar to those in common use; but in order to obviate the difficulties arising from the shakiness of some of those now used, the trouble in packing and expense of shipping others, and the excessive weight of them all rendering it

difficult to move them about the house when used in the family, I have constructed the frame as follows:

F represents a frame, which is made in one piece. It consists of two parts, *a b*, and two girts, *c d*. The posts curve outwardly at each extremity, and are secured to the table near to and parallel with the back edge thereof, thus forming a sufficient support to the table in the direction of its length. The two posts *G H*, Fig. 2, each of which has two short girts, *e f*, cast therewith, are secured to the back frame, Fig. 1, by means of the four screws, *g h i j*, thus forming the stand of three flat skeletons, which, when combined, possess in an extraordinary degree lightness and strength.

The frame, it is evident, may often be used to advantage in other than sewing-machines.

What I claim as my invention, and desire to secure by Letters Patent as a new and improved article of manufacture, is—

A self-sustaining skeleton treadle-frame composed of sections secured together at right angles, substantially as described, so that the frame is self-braced crosswise and lengthwise with the table which it supports.

H. C. SPALDING.
